UNITED STATES PATENT OFFICE.

EDWARD J. DARLING, OF PHILADELPHIA, PENNSYLVANIA.

FIGURE WHEELED TOY.

Application filed September 24, 1927. Serial No. 221,636.

My invention relates to toys and more particularly to mechanical figure toys.

An object of the invention is to provide a toy embodying a cart or vehicle and a walking figure arranged to simulate pulling the cart or vehicle.

The invention further provides a toy of this type wherein the legs and other movable parts of the figure are arranged to have free movement so that the figure will possess life like movements when moved over a plane surface.

With the preceding and other objects and advantages in mind, the invention consists in the novel combination of elements, constructions and arrangement of parts to be hereinafter specifically referred to, claimed and illustrated in the accompanying drawings, wherein:

20 Figure 1 is a side elevation of the toy, the broken line showing illustrating the relative portions of the wheels to impart walking movement to the doll or body embodied in the invention;

25 Figure 2 is a top plan view of the same; Figure 3 is a rear elevation;

Figure 4 is a vertical sectional view of the doll or body; and

30 Figure 5 is a fragmentary perspective of the latter.

Referring to the invention in detail a cart or two wheeled vehicle 5 having forwardly extending shafts or handles 6 is provided. Arranged between the forward ends of the shafts 6 is a doll or other suitable figure comprising a rectangular body 10 rigidly secured to the shafts by screws or other fastenings 11. The lower end of the body at opposite sides is notched or recessed as at 12 to receive legs 13, the latter having transverse openings 14 receiving the screws 11 to pivotally connect the legs to the body. Blocks or feet 15 having longitudinally curved or rounded under faces 16 are attached to the lower ends of the legs and contact with the surface over which the toy is moved.

To cause the legs to move in unison a horizontally disposed lever 17 is pivoted intermediate its ends centrally of the lower end of the body by a pivot pin 18 carried by the latter. Spherical heads or knuckles 19 are formed on the ends of the lever and are universally mounted in universal sockets or recesses 20 formed in the opposed faces of the legs 13. Arms or braces 21 are rigidly attached to the upper end of the body at oppo-

site sides and have their lower ends secured to the tongues or handles 6. A head 22 is provided for the body having a shank 23 disposed in a tapered recess 24 in the upper end 60 of the body.

The shank 23 adjacent its upper end is pivotally mounted on a pin 25 extending across the upper end of the recess and anchored to the body. 65

A weight element 26 is attached to the lower end of the shank to cause the latter with the head to oscillate from side to side as the toy is actuated.

As illustrated in Figure 1 the wheels 36 for 70 the cart or vehicle are eccentric or elliptical shaped so as to continuously raise and lower the cart and body 10 from side to side as the toy is pulled over a surface as by a string 27 attached to the body. As the toy is moved 75 over the ground the legs are moved to simulate walking.

This movement is accomplished as follows: The wheels alternately reaching positions with their longest axis vertical imparts a 80 transverse rocking movement to the cart and body, alternately lifting the feet off the surface, permitting the lifted foot to move forwardly by gravity. At this time the other wheel is in a position with its longest axis 85 horizontal to retain the other foot on the surface.

What is claimed is:

1. In a toy, a vehicle having a pair of parallel members, an upright body rigidly supported between the parallel members and having notches at opposite sides opposed to the parallel members, legs for the body, having their upper ends received in the notches and contacting with the parallel members, and pivot elements passing through the parallel members and legs and engaged with the body, and means for alternately swinging the legs to simulate walking as the vehicle is moved over a surface. 100

2. In a wheeled toy, a transversely oscillatory cart having a pair of parallel members, a figure toy including an upright body rigidly supported between the parallel members and having notches in its lower end each 105 of which being opposed to one of the parallel members, and legs pivotally mounted between the parallel members and opposed walls of the notches with the opposite faces of the legs contacting with the parallel members and said walls whereby the legs are held against lateral movement, the legs being 110

moved to simulate walking incident to the oscillatory movement of the cart as the latter is moved over a surface.

3. A figure toy comprising a vertically disposed body having a central recess which opens upon the upper end of the body and whose side walls are disposed in divergent relation, a head above the body having a depending shank disposed within the recess and carrying a weight at its lower end, and a pivot passing through the body and upper

end of the shank to support the head for oscillatory movement, the shank being adapted to contact with the divergent walls of the recess upon oscillation of the head and thereby limit the movement of such head in opposite directions. 15

Signed at Philadelphia, in the county of Philadelphia and State of Pennsylvania, this 12th day of September A. D. 1927.

EDWARD J. DARLING.
